LANTERN POST

Buell Moore, Houston, Tex., assignor to Wide-Lite, a division of Esquire, Inc., Houston, Tex., a corporation of Texas

Filed June 24, 1964, Ser. No. 80,549

Term of patent 14 years

(Cl. D48—31)

FIG. 1 is a front view of a lantern post showing my new design, the lantern being shown in broken lines for illustrative purposes only;

FIG. 2 is a rear view thereof;

FIG. 3 is a section view taken at 3—3 of FIG. 1; and FIG. 4 is a section view taken at 4—4 of FIG. 1.

I claim:

The ornamental design for a lantern post, as shown and described.
